UNITED STATES PATENT OFFICE.

ROBERT A. SCARBOROUGH, OF PHILADELPHIA, PENNSYLVANIA, ASSIGNOR TO THE
J. G. BRILL COMPANY, OF PHILADELPHIA, PENNSYLVANIA, A CORPORATION OF
PENNSYLVANIA.

SLIDING GUIDE FOR DOORS.

1,063,605.

Specification of Letters Patent.

Patented June 3, 1913.

Application filed March 9, 1912. Serial No. 682,713.

To all whom it may concern:

Be it known that I, ROBERT A. SCARBOROUGH, a citizen of the United States, residing in Philadelphia, Pennsylvania, have invented certain Improvements in Sliding Guides for Doors, of which the following is a specification.

One object of my invention is to construct an improved roller guide for folding doors, especially the vestibule doors of passenger car platforms.

A further object of the invention is to use a straight track and to arrange the roller guide so that the doors can be folded together and swung back beyond a right angle to the guideway, without jamming or straining the parts and without using a track offset at the end. This object I attain by mounting the guide rollers in sliding bearings, so that they will travel on a straight track and will allow the doors to be folded back of the right-angled line.

In the accompanying drawings:—Figure 1, is a side view of the upper portion of the inclosed platform of a passenger car, showing the doors in the closed position; Fig. 2, is a sectional plan view on the line 2—2, Fig. 1, showing the door in the closed position in full lines and in the open position in dotted lines; Fig. 3, is a side view, partly in section, showing the upper portion of the guide roller; Fig. 4 is an end view of a door, showing the rails in section; Fig. 5, is a plan view of Fig. 3, showing the doors in their closed position; Fig. 6, is a plan view showing the doors in the open position; and Fig. 7, is a perspective view of the roller and its slide.

A is the body of the car.
40 B is the roof of the vestibule.

B' is the head plate directly under the roof of the vestibule.

C, C are the doors, four in the present instance, connected by hinges c. The main door is attached to the rear post B² by hinges c'. The first and second doors are connected by outside hinges, and the second and third doors by inside hinges, and the third and fourth doors by outside hinges, so that when the doors are open they will swing on their hinges to the position shown by dotted lines in Fig. 2.

Directly back of the head plate B' are two straight rails b, b', spaced apart, and arranged to travel between these rails are the

rollers D. These rollers have flanges d, which extend over the rails b, b' and are mounted on pins e projecting from a slide E, V-shaped in cross section, as shown in Fig. 7, and adapted to V-shaped undercut 60 ways f on the bracket F having a depending plate f' secured to the door C. These brackets F are secured to the outer ends of the second and fourth doors, so that when the doors are opened the rollers D travel between rails b, b' to the position indicated in Fig. 2. It will be noted in said figure that while the doors are closed, the slide is retracted, as in Fig. 5, but when the doors are opened the slide is projected, as in Fig. 6. 70 The projection of the fourth door is more than the projection of the slide of the second door, due to the fact that the second door is farther away from the rails. Thus it will be seen that the rollers readily accommodate 75 themselves to the straight track, and the end of the track need not be offset to allow the doors to swing past the line at right angles to the rails.

In order to limit the movement of the 80 slide, I provide a pin g on the bracket F and this pin travels in a groove e' in the slide. By this construction the slide cannot become detached from the bracket.

While my invention is particularly adapted for use in connection with the vestibule doors of passenger cars, it can be used with other folding doors or sectional partitions without departing from the essential features of the invention. 90

Though I have shown my invention as applied to four doors hinged together, the invention is applicable to two doors, or to more than four doors, or to partition sections.

I claim:

1. The combination of two doors pivotally connected together, the first door being hung to a fixed post; a longitudinal guide rail above the doors; a slide arranged to move longitudinally on the outer end of the second 100 door and guided by the said rail so that it will travel over the guide rail when the doors are moved from the open to the closed position; the slide accommodating itself to the position of the doors when open. 105

2. The combination of two doors pivotally connected together; the first door being hung to a fixed post; longitudinal guide rails above the doors; a bracket at the outer upper end of the second door and having a longi- 110

tudinal slideway therein; with a slide adapted to the slideway and having a roller; said roller being located so as to travel between the fixed rails when the door is moved from the open to the closed position; said slide accommodating itself to the position of the doors when closed.

3. The combination of two doors pivotally connected together, the first door being hung to a fixed post; longitudinal guide rails above the doors; a bracket secured to the outer, upper end of the second door and having a slideway therein; a slide adapted to the slideway; a pin projecting from the slideway; a flanged roller mounted on the pin; a stop on the bracket for limiting the movement of the slide in one direction; and

two fixed longitudinal guide rails above the doors between which the roller travels when the doors are turned on their hinges. 20

4. The combination of two doors pivotally connected together; the first door being hung to a fixed post; longitudinal guides; a roller and a sliding connection between the guides and the second door; said sliding connection moving substantially parallel to the face of the said second door. 25

In testimony whereof, I have signed my name to this specification, in the presence of two subscribing witnesses.

ROBERT A. SCARBOROUGH.
